RACK FOR BOOTS AND SHOES

Filed Aug. 21, 1926

FIG. 1.

FIG. 2.

FIG. 3.

FIG. 4.

INVENTOR

Charles Fischer

BY M. J. Banning

ATTORNEY

UNITED STATES PATENT OFFICE.

CHARLES FISCHER, OF NEW YORK, N. Y.

RACK FOR BOOTS AND SHOES.

Application filed August 21, 1926. Serial No. 130,656.

My invention relates to boot and shoe racks and more particularly to such a rack provided with a pair of heel-supporting wire cross member frames and a plurality of pivoted clamps, adapted to engage the top portions of the counters or backs of the boots and shoes supported on the rack.

One of the objects of my invention is to provide each heel-supporting cross member with a bent portion, so as to provide it with one or more back stops which prevent backward play of the hanger and thus prevent the shoes from swinging.

Another object of the invention is to provide a plurality of swinging, gripping jaws mounted on each crossbar of the rack, which can be readily clamped to the top of the counter or back of the boot or shoe and which, with the heel-supporting frames, will firmly hold any style and size shoes in position.

With the above and other objects in view, my invention consists in the parts, improvements and combinations more fully pointed out hereinafter.

Turning now to the drawings:

Figure 1, is a perspective front view of my improved boot and shoe rack, showing the manner of holding boots and shoes.

Figure 2, is a vertical cross-section of the rack shown in Figure 1.

Figure 3, is a perspective view showing the rack collapsed.

Figure 4, is a detailed sectional view, showing the gripping jaws.

In the drawings, the rack with its side bars 1, 2, 3, 4, is supported on the inside of a door of a closet by means of screws 5, passing thru holes in the side bars. The upper side bars 1, 3, are pivoted to the lower side bars 2, 4, at 6, 7, thus allowing the rack to collapse, as shown in Figure 3. A projecting crossbar 8, is provided with side arms 9, which are pivotally mounted on the outer ends of the upper side bars 1, 3, and a similar crossbar 10, is pivotally secured to the outer ends of the lower side bars 2, 4. Each crossbar carries the means for supporting the shoes, the shoes being placed on a swinging frame which supports the heels and being clipped to the crossbar by means of gripping clips, which grip the top portions of the backs or counters of the shoes.

In the form of the invention illustrated,

each heel-supporting frame 11, 12, is provided with a back stop which limits the backward movement of the frame and shoes. The upper wire frame is bent at each end at 13, 14, and the lower frame at 15, 16, thus providing back stops for the respective wire frames.

Means are provided for gripping the tops of the backs of each shoe and securing the gripping jaws to the crossbars. A pair of gripping jaws 17, 18, pivoted at 19, and pressed together by spring 20, are provided, the jaws being opened to clamp the shoe, by finger-pieces 21, 22. Each pair of jaws is pivoted to a bracket 23, which, in turn, is pivoted to an elongated looped member 24, at 24^a, which loop encircles the crossbar so that it may be raised or swing freely upon it. This permits the looped member and gripping jaws to be placed in any of a series of positions so that the jaws will grip the tops of the backs of shoes of different heights and styles. One end of the loop is pivoted to bracket 23, carrying the jaws, the other member of the loop being sprung behind the pivot to which the bracket is attached, so as to provide a self-locking joint.

By means of the elongated loop the gripping jaws can be positioned so as to engage the backs of shoes of different heights, low shoes and high shoes. This allows the shoes to be suspended downwardly and the heel-supporting frame with its back stop maintains them away from the door.

In the best embodiment of the invention, the loop end has a shoulder 25, against which the gripping jaws swing by gravity, when the jaws are not gripping a shoe, these jaws being suspended from the loop by bracket 23. This positions the jaws so that the finger pieces are always readily accessible approximately at right angles when it is desired to clamp the jaws upon the top of the shoe back. The gripping ends of the jaws are bent so that the outer jaw will avoid marring the shoe and the inner jaw will firmly clamp upon the inside of the shoe.

Having thus described the invention, the operation will be clear. The heels of the shoes are supported on the wire frame and the tops of the backs are gripped by opening the gripping jaws and clamping them on the shoes. The shoes are thus firmly held, so as to project downwardly and away

from the door, without danger of falling off the rack when the door is opened and closed.

It will be understood that changes may be made in carrying the invention into effect, without departing from the principle of the invention.

What I claim is:

1. A shoe rack comprising in combination, a pair of side bars, a projecting crossbar, a wire frame pivotally mounted upon said crossbar and provided with a back stop to limit its backward movement, said wire frame having a cross member adapted to engage the heel of a shoe, and a plurality of clips, swinging about said crossbar and each adapted to engage the top portion of the back of the shoe.
2. A shoe rack comprising in combination, a pair of side bars, a projecting crossbar, a wire frame pivotally mounted upon said crossbar, said wire frame being bent at each end to form a back stop to limit its backward movement, said wire frame having a cross member adapted to engage the heel of a shoe, and a plurality of clips swinging about said crossbar and each adapted to engage the top portion of the back of the shoe.
3. A shoe rack comprising in combination, a pair of side bars, a projecting crossbar, a wire frame pivotally mounted upon said crossbar and provided with a back stop to limit its backward movement, said wire frame having a cross member adapted to engage the heel of a shoe, and a plurality of looped members swinging on said crossbar, and a plurality of clamps, each pivotally mounted on its looped member and each adapted to engage the top portion of the back of the shoe.
4. A shoe rack comprising in combination, a pair of side bars, a projecting crossbar, a wire frame pivotally mounted upon said crossbar and provided with a back stop to limit its backward movement, said wire frame having a cross member adapted to engage the heel of a shoe, and a plurality of self-locking looped members swinging on

said crossbar, each member having a shoulder, and a plurality of clamps, each pivoted on its looped member and adapted to engage said shoulder, said clamps adapted to engage the top portions of the backs of the shoes.

5. A shoe rack comprising in combination, a pair of side bars, a projecting crossbar, a wire frame pivotally mounted upon said crossbar and provided with a back stop to limit its backward movement, said wire frame having a cross member adapted to engage the heel of a shoe and a plurality of looped members swinging on said crossbar, each member having a shoulder, and a plurality of clamps, each pivoted on its looped member and adapted to engage said shoulder, each clamp comprising two pivoted spring-pressed gripping jaws, each having a finger piece end, and adapted to engage the top portion of the back of the shoe.

6. A shoe rack comprising in combination, a pair of upper side bars, a pair of lower side bars pivoted to the upper side bars, a projecting crossbar carried by each pair of side bars, a swinging frame for supporting the heels of the shoes carried by each pair of side bars and a plurality of clips, each mounted so as to swing about each crossbar and each adapted to engage the top portion of the back of the shoe.

7. A shoe rack comprising in combination, a pair of upper side bars, a pair of lower side bars, pivoted to the inner ends of the upper side bars, a projecting crossbar carried by the outer ends of each pair of side bars, a swinging frame for supporting the heels of the shoes, carried by each pair of side bars, and a plurality of clips, each having a pair of spring-pressed gripping jaws, said clips each mounted so as to swing about each crossbar and each adapted to engage the top portion of the counter of the shoe.

In testimony whereof, I have signed my name to this specification.

CHARLES FISCHER.
